Primary Examiner — George D. Kirschbaum*Assistant Examiner* — Clese Moore, Jr.(74) *Attorney, Agent, or Firm* — Tutunjian & Bitetto, P.C.(57) **CLAIM**

The ornamental design for a bicycle basket, as shown and described.

DESCRIPTION

FIG. 1 is a perspective view of the bicycle basket showing my new design;

FIG. 2 is another perspective view thereof;

FIG. 3 is a front view thereof;

FIG. 4 is a rear view thereof;

FIG. 5 is left side view thereof;

FIG. 6 is a right side view thereof;

FIG. 7 is a top view thereof; and,

FIG. 8 is a bottom view thereof.

The broken lines shown illustrate portions of the bicycle basket that form no part of the claimed design.
